Williams & Cutchard

UNITED STATES PATENT OFFICE.

NILES I. MEKEEL, OF YORKTOWN HEIGHTS, NEW YORK.

ELECTRIC IRON.

Application filed April 26, 1923. Serial No. 634,654.

To all whom it may concern:

Be it known that I, NILES I. MEKEEL, a citizen of the United States, and a resident of Yorktown Heights, Westchester County, 5 and State of New York, have invented a new and useful Improvement in Electric Irons, of which the following is a specification.

This invention relates to electric irons 10 and has for one of its important objects the provision in such a device, of a novel and improved means for retaining the resistance unit properly positioned within its pocket or channel and out of contact with the base- 15 plate without detracting from the efficiency of the unit as a source of heat supply for the base or ironing surface of the iron.

Another object of the invention is to provide an inexpensive and improved form of 20 guard for the external terminals to which the resistance unit is electrically connected.

A further object of the invention is to so construct, arrange and proportion the various elements entering into the device embodying my invention as to facilitate inexpensive manufacture and economic assembling thereof and yet provide a structure which is strong, durable and reliable in use.

30 Other objects and certain advantages of my invention will become apparent from the following description when taken in connection with the accompanying drawings in which

35 Figure 1 is a plan view of an electric iron embodying my invention.

Figure 2 is a central, vertical, longitudinal sectional view of the device embodying my invention.

40 Figure 3 is a face view of the internal element carrying the heating unit.

In the drawings wherein for the purpose of illustration is shown what I at present consider the preferred form of my invention, the numeral 5 indicates a base or base-plate of conventional design upon which is disposed an internal element 6 preferably constructed from soapstone or other suitable relatively heavy electrical insulating or dielectric material. This internal element is provided with a tortuous groove or channel 7 within which is arranged a heating element or resistance unit 8 in the form of a coil of electric resistance wire the opposite ends of which are electrically connected to a pair of contact terminals one

of which is shown in Fig. 2 and is indicated by the numeral 9, these terminals being provided, as will be readily appreciated by those skilled in the art to which my invention pertains, as a means for electrically connecting the iron in circuit with the house current by means of the conventional form of attachment plug, not shown. The terminals project through the heel portion of 65 the internal element and extend an appreciable distance into a pocket 10, they being held in their respective positions by means of nuts 11 in contact with which the opposite ends of the heating unit 8 are maintained by lock-nuts 12.

In order to retain the heating unit 8 within its groove or channel 7 under all conditions, I have provided a plurality of insulating strips 13 constructed from a suitable 75 insulating material, such as transparent mica. These strips are positioned within transverse grooves or channels 14 and are spaced from each other by means of interposed ribs 15 formed integral with the internal element 6. With the strips 13 positioned, as shown most clearly in Fig. 3, their opposite ends are maintained in contact with the outer wall 16 of the tortuous groove or channel 7, and by reason of such 85 they are maintained against transverse displacement, they being held against movement toward or away from each other by means of the interposed transversely disposed ribs 15. It will be readily appreciated from the construction that when the several elements of the iron are assembled, the insulating strips 13 will function under 90 all conditions to prevent the heating unit 8 from accidentally or otherwise coming in 95 contact with the base-plate 5. It will be noted that since the insulating strips 13 are spaced an appreciable distance from each other, a series of openings 17 are provided which permit a certain amount of heat 100 generated by the resistance or heating unit 8 to be transmitted directly to the base-plate 5 thus adding to the efficiency of the device in so far as transferal of heat to the base-plate 5 is concerned. It will be ap- 105 preciated that by providing strips of insulating material rather than a sheet thereof, the total area of the insulating material is relatively small as compared with the total area of the base-plate 5, or internal element 110 6.

The insulating strips 13 located at op-

posite ends of the internal element are relatively wide as compared with the intermediate strips such being necessitated by reason of the peculiar design or contour of 5 the channel 7, but in order to provide for the direct transfer of a maximum amount of heat to the base-plate from portions of the heating unit 8 adjacent the relatively wide insulating strips, I have cut the same 10 away; as shown at 17, thereby exposing certain portions of the heating element 8 which would otherwise be covered by these particular strips.

As an enclosure for the internal element 6, I provide a cover or casing 18 through 15 which the terminals 9 project, they being insulated from the casing by means of insulating washers 19. This casing is maintained in position upon the base-plate 5 and 20 the internal element 6 by means of bolts 20 passed through openings 21 formed in the internal element which bolts are maintained in screwthread engagement with the base-plate 5 at their respective screw-threaded 25 ends 22. Upon the rear of the casing or housing 18, there is disposed a heel rest 23 constructed from sheet metal which is bent into a U-shaped element, one leg, 24, of which is connected to the casing 18, as 30 shown at 25; whereas the other leg 26 is bent at an angle with respect to itself to provide an apron 27 which, in turn, is bent at an angle with respect to itself to provide a wing 28 secured to the casing 18 by means 35 of one of the bolts 20 which also functions co-operatively with the other bolt 20 as a means for retaining a conventional type of handle bracket 29 properly positioned.

In order to provide a guard for the terminals 9, I strike up from the leg 26 a tongue 40 30, the opposite ends of which are bent into a parallel relation with respect to each other to provide wings 31. As will be readily appreciated, the space afforded between the 45 handle bracket 29, the tongue 30 and the oppositely disposed wings 31, is adapted to receive the conventional type of attachment plug, not shown, by which the heating unit 8, as above mentioned, is placed in circuit 50 with the house current through the terminals 9. The guard formed by the tongue 30 and wings 31 above mentioned may be reinforced or strengthened by the provision of a bracket 55 32. This bracket is preferably constructed from sheet metal and is struck up to provide a tongue 34 leaving an opening 35 adapted to receive the conventional form of attachment plug, not shown; the tongue being adapted to co-operate with the attachment 60 plug to maintain the same co-operatively connected to the terminals 9. An apron 36 maintained in engagement with the upper end of the tongue 30 constitutes a continuation of the tongue 34 and may be 65 provided by turning down that portion of

the metal which would normally lie at the rear of the opening 35 from which the tongue 34 is struck.

It will be noted that the opening 35 formed by striking up the tongue 34 accommodates the handle-bracket 29 lending rigidity to the bracket 32 in addition to that which is afforded by reason of the fact that the upwardly projecting wing or lip portion 37 is secured to the bracket 29 and handle 38 by 75 means of the longitudinally disposed bolt 39 extending therethrough.

While I have shown and described what I at present consider the preferred form of my invention, it is to be understood that 80 various changes in the size, shape, proportion and arrangement of parts may be resorted to without departing from the spirit of the invention or the scope of the subjoined claims.

Having thus described my invention, I claim:

1. An electric iron having an internal element provided with a passage, a heating element arranged within said passage and means positioned upon the face of said internal element and extending across said internal element for retaining said heating element in position within said groove. 90
2. An electric iron having an internal element composed of insulating material having a groove formed therein, a heating element arranged within said groove and insulating elements extending across and recessed into the face of said internal element and overlying said heating element for retaining the same within said groove. 95
3. An electric iron having an internal element of insulating material provided with a groove, a heating element arranged within said groove and strips of insulating material extending across and recessed into the face of said internal element, said strips of insulating material being maintained in a spaced relation and overlying said heating element to retain the same within said groove. 100
4. An electric iron comprising an internal element provided with a groove and having a base-plate associated therewith, a heating element arranged within said groove and a plurality of retaining elements recessed into the face of said internal element and disposed intermediate said internal element and base-plate, said retaining elements being spaced from each other and disposed in an overlying relation with respect to said heating element for retaining the same in position within said groove. 105
5. An electric iron comprising an internal element constructed from insulating material and having a groove formed therein together with a plurality of channels, a heating element arranged within said groove and a plurality of retaining elements dis- 115

120

125

130

posed within said channels, said retaining elements being flush with the face of said internal element and disposed in an overlying relation with respect to said heating element for retaining the same in position within said groove.

6. An electric iron comprising a base plate, an internal unit, a cover for said unit, a handle bracket associated with said cover, a heel rest associated with said cover, said heel rest being provided with an apron co-operating with said cover and a wing disposed intermediate said handle bracket and cover, and means passing through said handle bracket, wing, cover, internal unit, and into engagement with said base plate for retaining said handle bracket, heel rest, cover, internal unit and base plate assembled.

7. An electric iron comprising a base plate, an internal element positioned upon said base-plate, a casing for said internal element, a heating element associated with said internal element, said heating element being provided with terminals, a heel rest associated with said casing, a portion of said heel rest being struck up to provide a guard for said terminals.

8. An electric iron comprising a base plate, an internal element positioned upon said base-plate, a casing for said internal element, a heating element associated with said internal element, said heating element being provided with terminals, a heel rest associated with said casing, a portion of said heel rest being struck up to provide a tongue having opposite sides bent to provide wings adapted to function co-operatively with said tongue as a guard for said terminals.

9. An electric iron comprising a base plate, an internal element positioned upon said base-plate, a casing for said internal element, a heating element associated with

said internal element, said heating element being provided with terminals, a heel rest 45 associated with said casing, a portion of said heel rest being struck up to provide a guard for said terminals, a handle associated with said casing, a bracket associated with said handle, said bracket being provided with an apron adapted to co-operate with said guard.

10. An electric iron comprising a base-plate, an internal element positioned upon said base-plate, a casing for said internal 55 element, a heating element associated with said internal element, said heating element being provided with terminals, a heel rest associated with said casing, a portion of said heel rest being struck up to provide a guard 60 for said terminals, a handle associated with said casing, a bracket associated with said handle, said bracket being provided with an apron adapted to co-operate with said guard and having an opening formed therein in 65 alinement with said terminals.

11. An electric iron comprising a base-plate, an internal element positioned upon said base-plate, a casing for said internal element, a heating element associated with 70 said internal element, said heating element being provided with terminals, a heel rest associated with said casing, a portion of said heel rest being struck up to provide a guard for said terminals, a handle associated with 75 said casing, a bracket associated with said handle, said bracket being provided with an apron adapted to co-operate with said guard and having an opening formed therein in alinement with said terminals, and a tongue 80 associated with said bracket, said tongue being disposed adjacent said opening.

In testimony whereof, I have affixed my signature to this specification.

NILES I. MEKEEL.
